TRAFFIC SIGNAL

Application filed December 24, 1928. Serial No. 328,194.

My invention relates to improvements in traffic signals.

The object of my invention is to provide a traffic signal for the control of both pedestrians and vehicles and of a design whereby one source of uncolored light illuminates the directional indicia.

Another object of my invention is to provide a traffic signalling device of a revolving type, and, on which the attention or warning signal is illuminated separately from the directional features and wherein the attention signal functions with the revolving means during which function the directional illumination is withheld.

A further object of my invention is to provide a revolving traffic signalling device driven by an electric motor and worm gear and with electrical relays in combination with a simple two wire remote control timing mechanism, the latter mechanism to control a plurality of signals on account of the simplicity of the arrangement of the electrical circuits.

A still further object of my invention is to provide a signal device for the control of traffic which has an auxiliary relay and remote control for use in warning and clearing traffic in case of the passage of fire department trucks, police cars, ambulances and the like, whereby the attention or hold signal will remain illuminated and the directional features will continue to revolve without light.

These and other objects will hereinafter be more fully explained, reference being had to the accompanying drawings which form a part of these specifications and wherein like characters apply to like parts in the different views.

Referring to the drawings:

Fig. 1 is an elevation of the traffic signal shown on a fragmentary part of a pedestal.

Fig. 2 is a plan view of Fig. 1.

Fig. 3 is a longitudinal section of the signal with parts removed for illustrative purposes.

Fig. 4 is a fragmentary cross sectional view with parts removed for illustration,

Fig. 5 is a schematic wiring diagram of the electrical connections.

A housing 1 rotatably mounted on the disk 2 has its uppermost portion a hemispherical globe 3 affixed in the manner shown.

The globe 3 being formed of opalescent glass and colored red or yellow as warranted.

The upper half of the housing 1 is windowed as shown with red glass for one direction and green glass for the other. The red glass indicated by 4 and the green glass by 5.

The visors 6 act as shields against the sun's rays during the day and vehicle and street illumination at night.

The lower half of the housing 1 has on each side an extended arm or subhousing 7, formed as shown, carrying the words "Stop" and "Go" on red and green glass windows respectively, the red glass being indicated by the numeral 8 and the green glass by the numeral 9.

With regard to Fig. 1 the signal "Go" on the right being for vehicles and pedestrians on the right side of the street. The signal "Go" on the left is designed for pedestrians on the left side of the street whose view of the other signal is obscured by the intervening "Stop" arm, which also may obstruct their view of the green glass on the upper half of the housing.

The "Stop" and "Go" indicia are protected by the visors 9 and 10.

Sub-glasses 12 of appropriate color are mounted in the sub-housings 7 as a precautionary measure against loss of color in the illumination at a window should it become broken.

A cylindrical skirt 18 is constructed below and integral with the housing 1.

The disk 2 is positioned on the pipe member 14 and carries on its upper surface the receptacle and electric light 15, and the glass cylinder 16.

The cylinder 16 has on its upper half the indicia of the streets or highways forming the intersection or junction.

These indicia are positioned with respect to the windows 4 and 5 and legible through the same when the interior of the cylinder is illuminated by the lamp 15.

Vans 17, affixed to the corners of the housing 1 and in approximate contact with the glass cylinder prevent cross illumination.

A cover 18 rigidly secured to the cylinder 16 at its top carries the receptacle and electric light 19, the latter functioning as illuminating means for the hemispherical hold or attention signal 3.

A gear 20 rigidly positioned below the disk 2 on the member 14 engages a worm 21 the same being affixed to a shaft 22 and driven by the electrical motor 23, the motor to be preferably of a single phase induction type.

A solenoid brake assembly 24 is affixed to the shaft 22, the purpose of which is to prevent a coasting or continuance of motor rotation after the energy supply circuit is opened.

The worm gear and shaft being trunnioned in the motor and outboard bearings which are rigidly affixed to the cylindrical skirt 13.

The rotation of the worm gear by the motor revolves the housing 1 and its component parts about the cylinder 16, which in company with the members affixed to the pipe 14 remains stationary.

A dial member 11 rigidly positioned on the pipe 14 below the gear 20 is fabricated from a dielectric or electro-insulating material and has on its upper surface the contacts or segments 25 and 26. A brush 27 positioned on and insulated from the arm 28 closes a circuit through the pipe 14 and connects the relays A and B in the box 30 on the cylindrical housing 30' with the dial contacts and lights.

Also connections are provided in the cable for the rings 31 positioned on the under surface of the disk 2.

The brushes 32 form the connecting means for the current supply from these rings to the motor.

Referring to the wiring diagram in Fig. 5:

The relay A and the directional light 15 are connected in parallel across the supply busses 5. The segments 25 and 26 with the brush 27 form a switch in series with this circuit as do the contacts on the relay B. The rotation of the brush 27 off of the segments 25 and 26 opens the light 15 and relay A circuit (also the energizing of the relay B will open this circuit).

When the light 15 and relay A circuit is opened on the dial or by the relay B, the de-energizing of the relay A closes a by-pass 55 over the drum switch D and energizes a circuit to the supply busses 5 comprising of the parallel connection of the solenoid brake, the motor, and the warning or attention light 19. As the closing segment on the drum switch 60 D is assumed to make momentary contact and then re-open, the closing of the segments 25 and 26 by the brush 27 as it revolves into position again lights the lamp 15 and energizes the relay A which opens the circuit controlling the motor and warning light, resulting

in a braking action from the solenoid brake assembly, thereby stopping the rotation of the housing 1.

The relay B, the same being auxiliary in its function, is energized from the supply busses through the closing of the switch F. It is assumed that this switch, of which there may be a plurality, is situated at the fire department headquarters and at convenient locations on the streets, available to the police for emergency use to warn and clear traffic.

When the switch F is closed the relay B is energized and the light 15 and relay A circuit is opened. The de-energizing of the relay A closes the motor and the warning light 19 circuit, the latter illuminating the hold signal during the revolving of the housing. This rotation continues until the switch F is opened whereupon the regular cycle of operation of the signal proceeds as determined by any timing mechanism desired on the drum switch D.

The control system has the following cycle of operation: Under normal conditions when traffic regulation is being handled, the drum switch D is rotated by a synchronous motor or clockworks and its speed of rotation is governed by the interval selected to most conveniently govern the change of traffic movement at an intersection. For example if fifteen seconds is allowed for each direction then the drum will be rotated at the speed of four revolutions per minute and if a period of twenty seconds is deemed necessary the drum will be set to rotate at the rate of three revolutions per minute. Or if it is found that one minute is necessary between traffic changes then the drum will be set to rotate one revolution per minute.

It will be assumed that the signal itself is in the position shown in Figs. 1, 2, 3, and 4. The brush 27 is across the segments 25 and 26 and the circuit energizing the lamp 15 and the relay A is closed and the armature of the relay A is lifted off of its contacts. The motor and the lamp 19 are deenergized and the solenoid brake 24 prevents any rotation of the worm 21 and any movement of the gear 20. The housing is thereby held immovable in the position shown with its interior illuminated by the lamp 15.

In the meanwhile drum D is in the process of rotation and after the duration of the pre-determined period it momentarily closes the switch circuit G. This immediately energizes the motor and lamp circuit 19, the solenoid brake instantly releases the motor to rotation, which rotation rotates the housing and removes the contact of the brush 27 with the segments 25 and 26 which results in an opening of the circuit feeding the lamp 15 and the relay A. This darkens the housing and illuminates the globe 3, the latter constituting the hold or warning signal as described. It should be noted that when the relay is deen-

ergized as herein stated the armature of the relay A is then released to close its contacts which maintains the supply of current to the lamp 19 and the motor circuit while the drum D proceeds in its rotation.

The housing is now revolving and there is no illumination in its interior, the globe is illuminated, the rotation progresses through an arc of ninety degrees whereupon the next pair of contacts 25 and 26 reach the position of the brush 27 and a circuit is closed to again energize the lamp 15 and the relay A. The armature of the relay is instantly lifted away from its contacts and the lamp 19 and motor circuit is opened. The solenoid brake prevents further rotation of the motor shaft and the housing becomes stationary in this position.

20 The interior of the housing is now illuminated by the lamp 15, the globe 3 is dark, the housing is stationary, instead of the "Go" indication as shown in Fig. 1 with green light the "Stop" indication with the red light is now visible.

25 After the drum D has made another revolution the circuit G is closed and the rotation occurs as heretofore described until the housing is positioned again as shown in Fig. 1 with the "Go" indication in evidence. This
30 is the normal procedure of my invention for the regulation of traffic, however I have provided another relay B which is energized through a switch F. This relay is arranged to open the lamp 15 and relay circuit A whenever the switch F is closed as heretofore described and breaks into the regular cycle of operation of the traffic control system whenever an emergency exists. It should be noted that the circuit governing the operation of
35 the lamp 15 and the relay A could be opened directly by the switch F, but on account of the fact that the station of the switch F may be at some distance from the signal itself the relay was installed to avoid the voltage drop
40 which would occur should the main current for the operation of the lamp 15 and relay A be passed over an appreciable distance and through a comparatively small wire, therefore the relay B allows the use of a rather
45 small conductor for connection to the switch F.

This circuit is adaptable to a plurality of signals all of which may be controlled by the one drum switch if so desired, by running a control bus for the G connection on each signal to one switch.

The design of my invention is arranged for both pedestal and pendant mounting. To adapt the signal shown for pendant mounting stay bolts are inserted between the members 18 and 2 to support the glass cylinder and the visors and indicia are inverted. This places the warning signal 3 at the bottom and the pipe 14 serves as a connecting means for suspension. The rotatable mount-

ing of the housing 1 on the disk 2 is operative both as shown and inverted.

The advantages of my invention over the traffic signals I have observed in use are in its control of pedestrians as well as vehicles, the rotatable housing with one directional light, and the synchronized action of the warning signal for emergency, which is operable from various points. 70

Also the remote control and timing circuit means is very simple and may be installed at a comparatively small expense. 75

An alternate system of traffic regulation, for a plurality of intersections is easily obtained by rotating the housings to their desired relative positions before closing the main circuit. 80.

I do not wish to be restricted to any particular manner of fabrication or material nor to any particular method of use, and such modifications may be employed as lie within the scope of the appended claims and what I do claim as new and desire to secure by Letters Patent is:

1. In a traffic control system; a rotatable signal having spaced Stop and Go indicating means thereon; means for rotating the signal including an electric motor; a motor circuit; a relay for closing the circuit to the motor when the relay is de-energized; means having a part operating in synchronism with said rotating means for energizing the relay at definite positions in the rotary travel of the signal and a periodically operated switch for closing the motor circuit; whereby the signal is successively rotated and stopped to display the Stop and Go indications.

2. In a traffic control system; a rotatable signal having spaced Stop and Go indicating means thereon; means for rotating the signal including an electric motor; a motor circuit; a relay for closing the circuit to the motor when the relay is de-energized; means having a part operating in synchronism with the rotating means for energizing the relay at definite positions in the rotary travel of the signal; a periodically operated switch for closing the motor circuit; a warning signal connected to be energized with the motor; an illuminating device positioned to illuminate the rotatable signal, said illuminating device being connected to be energized with the relay; whereby the signal is successively rotated and stopped to display the Stop and Go indications and whereby a warning indication is given when the signal is rotated.

In testimony whereof I affix my signature.

LEO M. TORRENCE.

CERTIFICATE OF CORRECTION.

Patent No. 1,758,481.

Granted May 13, 1930, to

LEO M. TORRENCE.

It is hereby certified that error appears in the above numbered patent requiring correction as follows: In the grant and in the heading to the printed specification the residence of the assignee is erroneously given as "Arlington, Kansas", whereas said residence should have been given as "Arrington, Kansas", as shown by the records of assignments in this office; and that the said Letters Patent should be read with this correction therein that the same may conform to the record of the case in the Patent Office.

Signed and sealed this 23rd day of September, A. D. 1930.

(Seal)
